COAL CONVEYER

Frederick Kalmbach, New York, N. Y., assignor,
by mesne assignments, to Electric Furnace-
Man, Inc., New York, N. Y., a corporation of
New York

Application August 27, 1935, Serial No. 38,034

9 Claims. (Cl. 198—37)

This invention relates to conveyer apparatus and more particularly to an improvement in an apparatus as described in the application of M. Dykstra, Ser. No. 35,914 filed August 13, 1935, for supplying solid fuel to the receiver portion of a stoker device.

An object of my invention is to provide an improvement in mechanism which is automatically regulated to supply the correct amount of fuel to such a stoker device and which may be cheaply manufactured and easily installed with new equipment or in combination with equipment already in use.

Another feature of my invention is to provide a mechanism which is compact and efficient, having substantially all the moving parts protected from the action of fuel such as coal.

Another feature of my improved construction is the elimination of noise by having only a small number of moving parts and having these parts so arranged that they may be readily bathed in lubricant. My apparatus is also adapted to be adjusted to suit different conditions, as will be more apparent from a detailed description of several embodiments thereof, illustrated in the drawings in which:

Figure 1 of the drawings illustrates a vertical section of one embodiment of my invention, shown mounted in position for use.

Figure 2 is a vertical section on the line 2—2 of Fig. 1.

Figure 3 is an enlarged horizontal sectional view of a portion of the operating mechanism showing one form of bearing construction.

Figure 2a is a sectional view similar to Fig. 2 but viewed from the opposite direction, illustrating a preferred ratchet and pawl drive and taken on the line 2a—2a of Fig. 3a.

Figure 3a is a view similar to Fig. 3 of this preferred ratchet and pawl drive.

Figure 4 is a horizontal section of Fig. 1, taken on line 4—4.

Figure 5 shows another form of mechanism which can be used to operate the pawl and ratchet device shown in Fig. 1.

Figure 6 is a view similar to Fig. 5 but illustrating a further modification of the operating mechanism.

Figure 7 is a vertical section through one end of my fuel conveyer showing a guard arrangement for the same.

Figure 8 is a vertical section of the top portion of another embodiment, which may be mounted as shown in Fig. 1.

Figure 9 is a vertical section of a further em-

bodiment of an operating mechanism for the fuel conveyer.

Figure 10 is a vertical section of a still further embodiment of an operating mechanism for the fuel conveyer.

Figure 11 is a view of the device shown in Fig. 10 as seen from the right hand side thereof, and having the top portion of the casing broken away to show the construction thereof.

Referring more particularly to Figs. 1, 2, 3, 10 and 4, numeral 10 indicates a receiver or other receptacle which is a part of a stoker arrangement such, for example, as that shown in the aforementioned application of M. Dykstra, in the Wightman Patent Re. 17,925, in the Hall et al. Patent #2,077,882, for supplying the coal to a burner in a furnace. Mounted upon this receptacle and preferably fixed thereto by bolts or the like is a casing 11 supporting in turn a rotatably mounted casing 12. On one side of the casing 12 a section 13 of a conveyer tube is pivotally mounted and loosely overlying a portion of said casing 12, to keep out any dust or dirt, there is provided a removable cover 14, having a handle 14a.

Coal or other solid fuel may be taken from a bin or other source of supply by means of the extension 15, connected to the conveyer section 13, and carrying a suitable helicoid member 16. This section 15 may be detachably mounted in the section 13 and held by the set screw 17. Power to turn the helicoid member 16 is supplied through the universal joint 18, positioned opposite the pivots in said conveyer section 13, by means of the shaft 19. This shaft 19 is adapted to be rotated in a bearing housing 20 which is bolted to the casing 12 by bolts 21, thus effectively sealing up a hole 22 in a partition in said casing to be more fully described hereafter. This bearing housing is fitted with a sleeve 200 of some suitable bearing metal having a head portion 201 which abuts the outer end of the bearing housing in assembled position.

Shaft 19 may be lubricated through a valved member 23 as customarily used with grease guns, or any suitable means applied to the threaded hole 24 in the bearing housing and sleeve. The portion of the shaft 19 between the universal joint 18 and the hole 24 may be hollow as illustrated at 240 and fitted with radial holes 241 adjacent the said hole 24 so that grease or other lubricant may be supplied to the universal joint which is preferably encased in a leather boot. A circular groove 242 is also provided on shaft 19 to facilitate the passage of lubricant.

55

The bearing sleeve 200 is preferably formed with a longitudinally extending grease groove 202 for lubricating shaft 19. Adjacent the inner end of said bearing member, and loosely mounted on the bearing sleeve head 201, is a collar 25 lubricated by means of the hole 203 in sleeve 200 and preferably shaped like a bell crank, having arms 26 and 26a projecting from the periphery thereof. The arm 26 is pivotally connected to the rod 27 by the pivot pin 28, while the arm 26a carries a pawl 29 pivotally mounted on the pin 30. This pawl 29 is adapted to engage a ratchet 31, which is also mounted on said shaft 19, and fitted cup-like over a reduced portion 32 of said collar 25. The hub of the ratchet is keyed to a collar 33 which is fixed to the shaft by means of a shear pin 34. The end of said shaft 19 projecting out beyond this collar is of square or some other irregular cross section forming a head 35 to which may be applied a crank for manually operating the helicoid. Mounted on a horizontal section of the casing 12 and immediately below the ratchet is a check pawl 36 pivotally mounted on the pin 39 and having an arm 37 to engage the ratchet and a weighted end 38 on the opposite side of the pivot 39 to hold said arm 37 in engagement with the ratchet.

The rod 27 is mounted for reciprocation in an inner vertical tubular section 40 of said casing 12, and a similar section 41 integral with the fixed casing 11 and registering with the tubular portion 40. Near the top of this section 41 is inserted an inner cylindrical casing 42 which may be screwed into place by means of the threads 43. The top portion thereof which projects up through the horizontal shelf 44 may be held in place by means of the nut 45. The casing sections 40 and 41 each extend to the casings 12 and 11 as shown in Fig. 5. The horizontal shelf 44, with the bearing support bolted at 21, separates the moving parts of the actuating mechanism under the cover 14 from the coal and dust and this shelf, together with the walls 40 and 41 and the horizontal closure wall 46 completely protect all of the moving parts so far described, with the exception of the universal joint and the helicoid conveying member, from any foreign material such as coal, coal dust, and the like, which are recognized to be very corrosive to metals.

Attached to the bottom of rod 27 by threads or other suitable means is a slender rod 47, which may be made of stainless steel or some other corrosion resistant metal, carrying a disc 48 at the lower end thereof. This rod passes through an aperture 49 in the horizontal section 46 and a washer 50 surrounding the rod 47 closes the said aperture 49. This washer member is preferably countersunk for a portion of its thickness so that the rod 47 will slide through it more easily as the rod reciprocates.

As illustrated more clearly in Figures 1 and 4, a rocker 54 is pivotally mounted on the shaft 56 which is supported at its ends in the bearings 56a integral with the casing 11 and is held there by set screws 56b. The rocker 54 has an arm 53 which extends into the casing 11 between the extended walls of the member 41 and is provided at its end with a ring 51 surrounding the rod 47 and having a cup shaped portion 52 adapted to receive the rounded end of the rod 27. The rocker 54 also has an arm 57 connected through the link 58 to a crank arm 59. These connections may be made by means of pivot pins 60 and 61 clamped in the crank arm 59 and the arm 57

respectively, by set screws and retained in the link 58 by cotter pins or other suitable means. The crank arm 59 may be mounted on the shaft 62 of a motor or other suitable driving means, but is preferably mounted on the shaft employed to drive the stoker mechanism from the reduction gearing 62.

Adjacent the outer or supply end of the coal conduit 15, I prefer to employ a guard member, such as shown in Fig. 7. This may comprise another helicoid member 65 connected to the helicoid 16 by means of the square or other irregularly shaped socket 65 on one end thereof and a cotter pin 66 passing through the square end of the shaft of the conveyer 16. This end of the coal conveyer structure may be blocked up by some suitable means 67 above the floor of the coal bin so that the whole structure is practically surrounded by coal. The helicoid 64 of this guard member has a much smaller pitch than the helicoid 16 and fits the tube 15 rather closely while projecting a substantial distance beyond the end thereof. It should be sufficiently strong to shear any lump of coal that may come between it and the end of the tube 15. In the use of this device any over-sized pieces of coal are either pushed away from the mouth of the conveyer tube or broken into smaller pieces before reaching the regulating mechanism and stoker.

In the installment of my device, the fixed casing 11 is first put in position by bolting, riveting, welding or the like, after which the rotatably mounted casing 12 and the actuating mechanism may be put in place, rotated to the correct position and clamped by means of the nut 45. The coal conveying tube 15 is next affixed and adjusted at the desired angle to the horizontal to supply coal from a bin or other source. The outer end or guard portions of this tube is then blocked up in suitable position, after which the casing 13 may be sealed to the casing 12 to prevent the escape of any gas or dust. Either permanent or temporary sealing means may be employed as long as it is effective for stopping up the cracks. The leather boot on the universal joint 18 may now be supplied with grease or other lubricant through the shaft 19 by way of the valved member 23. The pawl and ratchet mechanism may be suitably supplied with lubricant in any desired manner, preferably by means of wicks to insure constant supply of said lubricant and to thus reduce noise to a minimum. Coal may be started up the tube 15 by applying a crank to the head 35 until the receiver 10 is partly filled.

The driving mechanism for the stoker may be then started and will actuate the coal feeder as follows:

In the embodiment shown in Fig. 1, the rods 27 and 47 are raised by arm 53 of the rocker arm 54 which in turn is rocked by crank arm 59 through link 58. As rod 27 moves upwardly, collar 25 is rotated about shaft 19 and moves pawl 29 into engagement with ratchet 31. Further upward movement of rod 27 then rotates shaft 19 by means of ratchet 31 which is interlocked with collar 33; this collar is fixed to the shaft 19 for rotation therewith by a shear pin 34 passing through said collar and shaft. The shaft 19 rotates helicoid 16, acting through the universal joint 18, to bring fuel up the tube 15 and into the receiver 10 by way of casings 12 and 11. Shear pin 34 is made the right size to shear off if the helicoid or other parts become clogged. If so desired this pin may be accurately made to

withstand some definite predetermined force based on the strength of the other parts and to allow a suitable factor of safety therefor.

As crank 59 completes its rotation with the shaft 62, arm 53 is depressed allowing rod 27 to drop back by its own weight and pawl 29 thus moves counter-clockwise about shaft 19 (as viewed in Figure 2) slipping over a few teeth on ratchet 31. At each successive upward stroke of rod 27, shaft 19 is rotated to bring coal into the receptacle 10, the rate of rotation being such as to supply slightly more coal than is needed by the furnace. A constant supply of fuel is thus available at all times in the receiver 10.

As the amount of fuel accumulates and builds up in this receiver 10, however, the downward movement of rod 27 is restricted because of the disc 48 striking the top of the pile of fuel 48a. When the rod drops down only part of the distance of its normal stroke under these conditions, the cup shaped ring 51 is disengaged from the bottom of rod 27 until the crank arm 59 is rotated sufficiently to bring said ring back into such engagement. It is apparent from the foregoing that if rod 27 drops down only half of its normal stroke, for example, the next upward stroke will be only half of the normal stroke and the helicoid 16 will thereby be rotated only half the normal amount. Considering the shaft 62 to be rotating in a clockwise direction, rod 27, as shown in Fig. 1, will remain in its illustrated position while shaft 62 turns through 180°. Ring 51 will at that point re-engage the base of rod 27 and lift it one half of a normal stroke. While the operation of a half normal stroke has been described as illustrative, it is clear that the length of stroke will vary according to the amount of fuel in the hopper and casing and that if sufficient fuel piles up under disc 48, the reciprocation of rod 27 will be automatically stopped thus cutting off further supply of fuel to the receiver until some of said fuel is withdrawn therefrom. It is understood that some suitable stoker arrangement (not shown) is provided, preferably at the base of receiver 10 comprising means for feeding fuel from the receiver 10 to a burner as in a furnace. As such feeding takes place after supply of fuel to the receiver has stopped as described above, the coal level in the receiver drops and the rod 27 again starts to reciprocate to replace the fuel withdrawn.

A preferred bearing structure and ratchet drive is illustrated in Figs. 2a and 3a which may be readily substituted for the structure shown in Figs. 2 and 3.

In this preferred form, shaft 19 is rotatably mounted in bearing sleeve 200 fitted to bearing housing 20. This housing 20 is fastened to casing 12 by means of bolts 21. Shaft 19 carries an axial hole 240, circular groove 242, and radial hole 241 and sleeve 200 is formed with a longitudinal groove 207, radial hole 203, and an opening registering with the threaded hole 24 in the housing all substantially the same as heretofore described in connection with Figs. 2 and 3.

This embodiment differs in that the ratchet 31c which is mounted directly on the bearing sleeve head 201 is wider than ratchet 31 and aligned with reciprocating drive rod 27c thus reducing bending strains in shaft 19.

Two link members 310, 310 are rotatably mounted on the ratchet hub, the outer member being held in place by suitable means such as retaining ring 311 which may be formed of spring steel and simply snapped in place in a groove 312

in the ratchet hub. The outer ends of these links carry the pivot pin 28c on which is also mounted the reduced end 270 of rod 27c and the bifurcated end or arms 290, 290 of pawl 29c. Pawl 29c is preferably held in engagement with ratchet 31c at all times by a spring member such as the spring 291.

Ratchet 31c may drive shaft 19 through collar 33 and shear pin 34 as heretofore described. Rod 27c is preferably cut away at 271 to allow ample clearance with the ratchet 31c.

It is very desirable to also employ a check pawl such as shown at 36c pivotally mounted on pin 39c having an arm 37c engaging the ratchet and an oppositely disposed weighted arm 38c to hold said arm 37c and ratchet in engagement. This check pawl preferably is positioned to afford a certain amount of backlash to the apparatus thus insuring that the check pawl will always be effective despite small variations in mounting the apparatus and slight variations in size of the parts.

A check pawl is extremely helpful when large pieces of fuel are being broken by the inlet guard at the end of the stroke of the drive rod.

The bearing and ratchet assembly of Figs. 2a and 3a operates in substantially the same manner as the embodiment just described but is preferred because of its simplicity and sturdiness of construction and substantial elimination of bending strains from the main drive shaft 19.

Other mechanisms for operating the rod 27 of my feeding device are illustrated in Figs. 5 and 6. In the device shown in Fig. 5, the rod 27 is reciprocated by means of an arm 68 pivoted at one end on the pin 70, supported from the casing 11, and having at the other end a cup shaped member 69, similar to the ring 51, for engaging the lower end of rod 27. This arm 68 carries a roller 71 rotatably mounted on the shaft 72 which acts as a follower and is held against the cam 73 by means of a spring 74. Cam 73 may be mounted on shaft 74a by means of a set screw 75 and the shaft 74a may be driven in any suitable manner as by the chain 76 and sprocket 77.

The operation of the modification shown in Fig. 5 is similar to that of Fig. 1 with the exception that different mechanism is used to raise the rod 27. Ring 69 on arm 68 engages the base of this rod in the same manner as ring 51 but arm 68 is rocked by a cam and follower structure built into the casing 11, instead of the crank arm device of Fig. 1. If desired shaft 74a may be driven by the reduction gearing as in the preferred modification. Spring 74 holds follower 71 in engagement with the cam or eccentric 73 but this is not essential to the operation of this device. However, in practice, ring 69 occasionally sticks to the base of rod 27 after the disc 48 comes to rest on the pile of fuel, thus breaking the contact between follower 71 and cam 73. This sticking is usually only momentary but of sufficient duration to allow the follower and cam to become distinctly separated, so that when the ring 69 disengages from rod 27, the follower is dropped with some force onto the cam. Some means of maintaining the cam and follower in engagement is therefore desirable.

Referring more particularly to Fig. 6 which illustrates an operating mechanism similar to that shown in Figs. 1 and 5, the rod 27 is operated by an arm 53a, carrying the cup shaped ring 51, mounted on a rocker 54a as shown in Fig. 4. Integral with the rocker 54a there is a downwardly extending arm 79 carrying a roller 75.

80 on a pin 81 at the lower end thereof. This roller acts as a follower working on the cam 82 which is mounted on the shaft 83, driven by any suitable means, such as the shaft from the reduction gearing 63. With this arrangement, the length of the stroke of the rod 27 may be easily adjusted by regulating the distance between the casing 11 and the cam 82.

The embodiment of Fig. 6 operates similarly to the preferred construction but the arm 53a is rocked in a slightly different manner. Rocker 54a is provided with a downwardly depending arm carrying a roller follower 80 which bears on a cam or eccentric 82. It will be apparent that as shaft 83 is rotated in either direction from its illustrated position, the arm 79 will be pressed in toward the casing 11, thereby raising arm 53a and rod 27. As rotation continues, these parts will move in the opposite direction thereby allowing rod 27 to drop back as described with respect to Fig. 1.

If desired a spring may also be used to keep the follower in engagement with the cam as described above in connection with Fig. 5.

Figs. 8 to 11 illustrate other modifications of my operating means by which the rod for actuating the pawl may be reciprocated by mechanism above the fixed casing 11 while retaining many of the advantages of my preferred constructions just described. As shown in Fig. 8 the rotatable casing 12a is mounted on a rim 84 of the casing 11a and may be clamped in place when suitably adjusted by the set screw 85. Above and to one side, preferably integral with said casing 12a, is an extension 86 carrying the upper end of the coal conveyer and a pawl and ratchet construction like that described with reference to Fig. 1. This extension 86 is hollow and provides a shaft through which the coal from the end of the conduit 15 passes to the casing 12a. Another arm 26b of the rocker arm 25a carries a pawl 29a by the pin 30a for engagement with the ratchet 31a like the ratchet and pawl construction shown in Fig. 1. A rod 87 carrying a collar 88 is pivotally mounted in the arm 26c by the pin 28a.

The lower end of rod 87 carries a smaller rod 89 which may be fixed thereto or pivotally suspended by the pin 90. This smaller rod in turn carries a weight 91 of suitable size and shape. Rod 87 passes down through a central opening 92 in the casing 12a which may be provided with a guard or bushing member 93. Rod 87 is reciprocated by means of a rocker arm 94 pivoted on pin 95 mounted on top of an upwardly projecting member 96 fixed to the casing 11a. One end of this rocker arm carries a fork 97 contacting the rod 87 below the collar 88, while the other end of said rocker arm comprises a ring 98 loosely supporting the link 99. Link 99 is pivoted at its lower end on the pin 100, which forms a part of a crank arm 101 driven by any suitable means, such as the gearing 102. The stroke of the rod 87 may be easily adjusted by shortening or lengthening the link 99 by means of a nut 103 and lock nut 104. The length of stroke of said rod may be varied by changing the length of crank arm 101.

In the modification illustrated in Fig. 8, fork 97 on the rocker arm 94 strikes the collar 88 fixed to the rod 87 to raise the same. This rocker arm is rocked by crank arm 101 through the link 99. Fork 97 may disengage from collar 88, if coal piles up under the weight 91, thereby limiting the stroke of the rod 87. If desired a second

collar may be employed on the rod 87 immediately below fork 97, in which case, the link 99 will simply slide upwardly through the ring 98 when the downward stroke of rod 87 becomes limited.

The device shown in Fig. 9 is similar to that just described, with the exception that rod 89a carrying a weight similar to 91, is pivoted on a pin 105 at one end of a link member 106 which is operated from above by a cable. This link is pivoted at its central portion on the pin 28a in the arm 26c and is supported at its upper end by a cable 107 running over a sheave arrangement 108. This sheave is carried by a standard 109 mounted in a collar 110 which is preferably integral with the casing 11a. The cable may be reciprocated in any desired manner, as by a crank arm actuated by the shaft from the reduction gearing.

In the device of Fig. 9, cable 107 may be reciprocated by a crank arm or other suitable means (not shown) to raise rod 87. This cable being flexible will not serve to actively push rod 87 downwardly when the lower end thereof strikes fuel in the hopper. Suitable guard means should be provided for said cable to prevent it from coming off the sheave 108 under such conditions. The end of the cable may be arranged to slip through an opening in link 106 if desired, so that a relatively heavy inflexible cable may be employed.

In the device shown in Figs. 10 and 11, there is a rod 111, similar to the rods 47 and 89 which carries a cup or weight at its lower end. The upper end of rod 111 is loosely mounted in a bushing member 112, which may be fixed to the casing 12a in any suitable way as by the threads 113. The top portion of this rod is connected to a yoke 114 carrying a roller follower 115 on a pin 116 near the top portion thereof. This top portion comprises a ring shaped section 118 carrying a set screw 118a for holding the link 117 which in turn is pivotally mounted on the arm 26c by pin 28b. Cam 119 fixed to the shaft 120 is adapted to move said follower 115 to raise the rod 111 and yoke 114. The shaft 120 is mounted in a suitable bearing 121 carried on the base 122, which is attached to the casing 12a by a ring 122a held by bushing 112 and by bolt 123a to the block 123. This shaft 120 is rotated by the chain 124 on the sprocket 125 which is driven in any suitable manner.

As illustrated this modification shows a slightly different arrangement of the various elements on the shaft 120. The ratchet 31b is mounted adjacent the bearing 20b and fixed to the shaft 55 by the shear pin 34b. Collar 25a carrying arms 26b and 26c is rotatably mounted on the shaft adjacent the head 35b. Thus the positions of collar 25a and ratchet 31b are the reverse from that shown in Fig. 1 to enable said collar to be placed directly over the reciprocating rod 111.

In this modification rod 111 and yoke 114 carrying said rod are raised by the rotation of cam 119 acting on the follower 115. Said cam may be rotated about shaft 120 in any desirable manner as by gearing or the chain 124 and sprocket 125. In order to rotate casing 12a about casing 11a, it is necessary to first loosen bushing 112 and set screws 85 and 118a. After the desired rotation has been effected, follower 115 is realigned on cam 119 and the said bushing and set screws again tightened. As an alternative the set screw 118a may not be loosened until after rotation has been effected and it is desired to realign the cam and follower.

In each of these embodiments the reciprocating rods are not positively moved downwardly but drop by their own weight. If more weight is needed to effect this downward movement the disc at the bottom of the rods may be weighted as shown at 48 in Figs. 6 and 8, or springs may be applied to effect this movement.

It will be noted that in several of the various embodiments shown and described, the upper casing carrying the helicoid conveyer may be rotated through an angle of 360° after the lower casing has been affixed to the receptacle that is to be supplied with coal.

An important feature of my invention, as shown in the various modifications, is the protection of all the moving parts, from the corrosive action of coal or other fuel. The gauge rod and its weight or disc may be made of stainless steel, but it would be very expensive to make a considerable portion of the apparatus out of this or any of the other expensive noncorrosive alloys.

In the operation of my invention the movable parts requiring lubrication are always accessible and it is not even necessary to stop the mechanism for adjustment, inspection, or lubrication.

The embodiments of my invention shown in Figs. 1-6 and 8 are illustrated with rings or forks 51, 69 and 97 engaging the reciprocable gauge rods and with this construction it is necessary to allow some play between the rod and the collar 25 and/or the collar 25 and the shaft 19, because these rings are fixed to arms pivoted about a horizontal axis and therefore describe an arc instead of moving strictly vertically. This play is only necessary when the apparatus is to be mounted as shown in Fig. 1, since the rotation of casing 12, 90° from this position would render the pin 28 parallel with the axis of rocker arm 54 eliminating this difficulty. As an alternative to allowing play between the members designated, which at most is very slight, I may employ parallel fingers or a forked end on the pivoted arms in place of the rings.

Various changes may be made both in the operation and construction of my improved apparatus without departing from my invention. While the various modifications shown have been described as fuel conveying mechanism and mounted on a stoker, it is manifest that the apparatus is suitable for handling other solids and may be used wherever it is desired to automatically regulate the amount of material conveyed to a receptacle in accordance with the amount of said material already in said receptacle.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. In a device for conveying solid fuel, a receiver, a conveyer for supplying fuel to said receiver, a shaft for driving said conveyer, a ratchet wheel fixed to the shaft, a rotatably mounted rocker having an arm, a pawl on said arm adapted to engage the ratchet, means for rocking said rocker and pawl, and means carried by said last named means for regulating automatically the extent of movement of said rocking means in accordance with the amount of fuel in said receiver.

2. In a device for conveying solid fuel, a receiver, a conveyer for supplying fuel to said

receiver, a shaft for driving said conveyer, a ratchet wheel fixed to the shaft, a rotatably mounted rocker, a pawl on one arm of said rocker for engaging the ratchet, reciprocable driving means attached to said rocker, and means carried by said driving means into contact with fuel in the receiver for regulating reciprocation thereof in accordance with the amount of fuel in said receiver.

3. In a device for conveying solid fuel, a receiver, a conveyer for supplying fuel to said receiver, a shaft for driving said conveyer, a ratchet wheel fixed to the shaft, a rotatably mounted rocker having an arm, a pawl on said arm adapted to engage the ratchet, reciprocable driving means centrally disposed with respect to said receiver attached to said rocker, and gauge means carried by said reciprocable means adapted to contact fuel in said receiver and thereby regulate the reciprocation thereof in accordance with the amount of fuel in the receiver.

4. In apparatus for conveying solid fuel, a casing, means for conveying fuel to said casing, a shaft driving said conveying means and carrying a ratchet thereon, a vertically reciprocable rod operating a pawl at its upper end for engaging said ratchet and a member at its lower end for contacting coal in said casing thereby limiting reciprocation of said rod, and means intermediate the ends thereof for raising said rod.

5. In apparatus for conveying solid fuel, a casing, means for conveying fuel to said casing, a shaft driving said conveying means and carrying a ratchet thereon, a vertically reciprocable rod operating a pawl at its upper end for engaging said ratchet and a member at its lower end for contacting coal in said casing thereby limiting reciprocation of said rod, and means comprising a rocker arm for reciprocating the rod from a position intermediate the ends thereof.

6. In apparatus for conveying solid fuel, a casing, means for conveying fuel to said casing, a shaft driving said conveying means and carrying a ratchet thereon, a vertically reciprocable rod having a pawl at its upper end for engaging said ratchet and a member at its lower end for contacting coal in said casing thereby limiting reciprocation of said rod, and cam operated means intermediate the ends thereof for raising said rod.

7. In apparatus for conveying solid fuel, a casing, means for conveying fuel to said casing, a shaft driving said conveying means and carrying a ratchet thereon, means connecting said shaft and said ratchet so constructed that this connection is broken when a predetermined torque is applied to said shaft by said ratchet, a vertically reciprocable rod having a pawl at its upper end for engaging said ratchet and a member at its lower end for contacting coal in said casing thereby limiting reciprocation of said rod, and means for raising said rod.

8. In apparatus of the character described, a receiver, a casing mounted on said receiver, means for conveying fuel to said casing including a shaft, a ratchet on said shaft, a vertically reciprocable rod operating a pawl at its upper end for engaging the ratchet, a check pawl engaging said ratchet, and gauge means movable into contact with fuel in said receiver for regulating the reciprocation of said rod in accordance with the amount of fuel in said casing.

9. In apparatus for conveying solid fuel, a receiver, a casing mounted on said receiver, means

for conveying fuel to said casing, reciprocable means centrally disposed within said casing for operating said conveying means, and reciprocable gauge means carried by said operating means and centrally disposed in said casing for controlling the extent of movement of said oper-

ating means to vary the amount of fuel conveyed in accordance with varying heights of fuel in said receiver, said casing being rotatable about a vertical axis through an angle greater than 360°.

FREDERICK KALMBACH.
